DOOR LOCK

Henry G. Voight and Frank B. Gerard, New Haven, Conn., assignors to Sargent & Company, New Haven, Conn., a corporation of Connecticut

Application October 25, 1940, Serial No. 362,810

16 Claims. (Cl. 70—153)

This invention relates to door locks, and more particularly to locks adapted for use upon the outer doors or front doors of houses, and commonly known as front door locks. It will be understood, of course, that the present locks are not necessarily confined to this use, but may be employed in any situation where they are found desirable.

In the past locks suitable for use upon front doors have been relatively complex in construction and of relatively high price, due to the fact that they must have provision for opening from the outside either by means of a key or by a knob or latch without the use of a key, and that they also must be provided with a knob or the like by which they may be opened from the inside, and also locked or dogged from the inside. In the present instance the mechanism of the lock structure per se is embodied in a tubular case and is of very simple construction, such, for example, as that shown in the Shaw Patent No. 2,124,897, granted July 26, 1938. This lock is provided with key-operated means at the outside of the door and manually operated means at the inside of the door to withdraw the bolt. We have converted such a lock into a front door lock by the addition of mechanism carried by plates or escutcheons upon the faces of the door to operate or withdraw the bolt from the outside of the door, and to dog the operating means at the inside of the door. Moreover, these additional functions are performed by mechanism very simple in character so that a complete and satisfactory front door lock may be constructed at a comparatively low cost, which lock will at the same time have all of the functions desirable in a lock of this character.

One object of the invention is the provision of a simple and inexpensive front door lock.

A further object of the invention is the provision of a front door lock having a tubular case housing the lock bolt and the immediate operating mechanism therefor, while providing means without the case for operating this mechanism and also dogging the same against operation.

A still further object of the invention is the provision of a front door lock which may be installed upon a door with a minimum amount of labor.

To these and other ends the invention consists in the novel features and combinations of parts to be hereinafter described and claimed.

In the accompanying drawings:

Fig. 1 is a front elevational view of a portion of a door upon which our improved lock has been mounted;

Fig. 2 is a sectional view on line 2—2 of Fig. 1; Fig. 3 is a sectional view on line 3—3 of Fig. 2; Fig. 4 is a sectional view on line 4—4 of Fig. 1; Fig. 5 is a front elevational view of a portion of

5 the lock cylinder;

Fig. 6 is a sectional view on line 6—6 of Fig. 5;

Fig. 7 is a sectional view on line 7—7 of Fig. 4;

Fig. 8 is a view similar to Fig. 7 showing the parts in another position; and

10 Fig. 9 is a view similar to Fig. 7 showing a modification of the invention.

To illustrate a preferred embodiment of our invention, we have shown a portion of a door 10 having an opening 11 bored through the front edge thereof to receive the cylindrical lock case 12. Mounted in this case is a reciprocating bolt 13 herein shown as a beveled latch bolt, and also a guard bolt or dog-controlling plunger 14. The construction of the lock case 12 and the mechanism for operating and controlling the bolt 13 may be the same as that shown in the Shaw Patent No. 2,124,897 already referred to. Further description, therefore, of this mechanism is unnecessary here, except that it may be said that the bolt-operating mechanism comprises a rotating or oscillating hub 15, shown in Fig. 4.

This hub is provided with a non-circular opening to receive an operating spindle 16 of similar shape by which the hub is rotated. One end of 30 this spindle is provided with a lost-motion connection with the key barrel 17 of a cylinder lock 18 mounted in a lock housing 19 on the face of an escutcheon plate 20 at the outside of the door. To provide such a connection a sleeve 21 (Fig. 6) 35 is secured to the key barrel by means of the pin 22, which sleeve is provided with an annular inwardly projecting flange 23, from which flange projects a lug 24. Secured to the end of the spindle 16 is a member having a disk-like portion

40 25 located within the sleeve 21 so as to be retained by the flange 23, and an outer circular portion 26 lying in the plane of the flange 23 and having a projecting nose 27 adapted to be engaged by the lug 24. It will be apparent that with the

45 parts in the position shown in Fig. 5, as they are when the door is closed and the latch bolt 13 protracted, the key barrel may be turned through substantially half a revolution before the lug 24 will strike the part 27 and initiate movement of the spindle 16. Likewise the spindle 16 may be turned by means to be described hereinafter through substantially one half a revolution before further rotation is prevented by the lug 24.

It will, of course, be understood that the key barrel is operated by the key 28 in the usual

manner from the outside of the door, and it will also be noted that the lock case is provided upon each side with lugs 29 designed to receive screws 30 by which the key-operated lock is secured in place. The escutcheon 20 is provided with a suitable opening 31 permitting the end of the lock to extend therethrough, and the housing 19 may be provided with a depressed seat 32 to receive the cap 33 of the lock, so that the housing 19 is likewise secured in place by the screws 30.

The door is provided with a relatively large transverse opening 34 within which extends the rear end of the lock case 12, and also the rear end of the key barrel and the associated parts. The screws 30 extend through this opening and through the lugs 29 on the lock case, and also extend through a plate 35 secured upon the inside of the door, the plate being of a size and shape to cover the opening 34. A hollow hub or sleeve 36 is rotatably carried by this plate and held against longitudinal movement thereto by means of a shoulder 37 on the sleeve and a pair of semi-circular rings 38 which fit in an annular recess 39 in the hub, and are held in place by a split spring ring 40. The sleeve 36 is provided adjacent its front end with an opening 41 which non-rotatably and slidably receives the spindle 16. It will thus be seen that allowance is made for doors of varying thickness, as considerable room for adjustment is permitted in the sliding engagement between the sleeve 36 and spindle 16.

An escutcheon plate 42 may be mounted upon the inside of the door, this escutcheon covering the plate 35. The escutcheon plate carries a socket or bearing 43 within which is rotatably mounted a knob 44, the knob being threaded upon a non-circular knob spindle 45 to which it is secured by the screw 46. The spindle 45 is secured by means of a pin 47 in the enlarged outer end of the sleeve 36. It will be obvious, therefore, that rotation of the knob at the inside of the door will serve to actuate the spindle 16 and therefore the latch bolt 13, and that rotation of the knob is permitted independently of the key barrel of the lock by means of the lost-motion connection between the spindle 16 and the key barrel, as shown in Figs. 5 and 6.

Upon the plate 35 at the inside of the door is mounted certain mechanism which is designed to be operated by a thumb latch at the outside of the door to rotate the spindle 36 and retract the latch from the outside by means other than the key 28. To this end the outer portion of the sleeve 36 is provided with an arm 50 which rotates with the sleeve. Above this arm the plate is provided with a boss or abutment 51 forming a stop for the arm 50, so that when the knob is rotated this rotation will be arrested when the arm 50 strikes the stop 51 in order to take the strain from the sleeve 36 and spindle 16 and associated parts. It sometimes occurs that when a bolt is retracted by a knob considerable force is applied to the latter, and when the bolt reaches its final retracted position, this force will serve to shear off any parts which may not be strong enough to withstand it. The stop 51 engaging the arm 50 thus relieves other parts of the lock of this strain.

Also pivotally mounted on the plate 35 at 52 is a lever 53 the lower side of which is engaged by a lever 54 pivoted to the plate at 55. The plate is provided with an elongated opening 56 through which extends the end of a thumb latch 57 pivoted at 58 to a reinforcing member 59 secured to the plate 20 at the outside of the door. 70

Below the thumb latch 57 is a handle 60 secured at its lower end to the door by a screw 61 and secured at the upper end against the plate 20 by means of the screw 62, which extends through the plate 35 at the inside of the door. The handle 60 is provided with a sleeve 63 designed to pass through the plate 20 and receive thereon a nut 64 to secure the handle to the plate. Thus it will be seen that the plate 20 at the outside of the door and the plate 35 at the inside are held in place by means of the screws 30 and 62.

It will be obvious that with this construction anyone at the outside of the door may operate the thumb latch 57, and thus move the levers 53 and 54 from the position shown in Fig. 7 to the position shown in Fig. 8, thus rotating the sleeve 36 and withdrawing the latch bolt 13. Thus the bolt may be withdrawn by the knob at the inside of the door, and by the key or thumb latch 57 at the outside of the door. The latter, of course, actuates the sleeve 36, and also the inside knob 44, which is non-rotatably connected with the sleeve.

In order that the thumb latch may be dogged against operation from the outside, a hub 65 is rotatably mounted in the plate 35 and carries a hook-shaped arm 66 at the inside of the plate, which hook is adapted to engage over the top of the inner end of the thumb latch 57 to prevent the inner end of this latch being raised and therefore prevent operation of the lever 54. The hub 65 is provided with a non-circular opening 67 in which is received a spindle 68 of similar shape, which spindle is operated by a thumb turn 69 rotatably mounted in the escutcheon 42. The hub 65 may be provided with flattened portions 70 against which acts the end of a spring 71 secured at the inside of the plate 35 to releasably maintain the hook 66 in operative or inoperative positions.

When it is desired to lock the door against ordinary operation from the outside, the thumb turn 69 is rotated to swing the hook 66 over the inner end of the thumb latch 57 and prevent depression of the outer end of this latch. It is then necessary to use the key 28 to open the door from the outside.

In Fig. 9 of the drawings we have shown a somewhat modified form of our invention, in which the lever 53, heretofore described, is omitted. The arm 50 secured to the sleeve 36 is operatively connected to the lever 54, which is actuated by the inner end of the thumb latch 57 by a link 75 pivoted at its upper end to the arm 50 and at its lower end to the lever 54. It will be apparent that the operation of the parts will be the same as already explained in connection with the form of our invention shown in Figs. 1 to 8. That is, the depression of the outer end of the thumb latch 57 will raise the lever 54, and therefore rotate the arm 50 in a counterclockwise direction, as shown in Fig. 9, against the stop 51, thus rotating the sleeve 36 and withdrawing the latch.

It will be obvious that in both forms of the invention we have provided a lock suitable for a front or outside door of a building, which possesses all of the functions necessary in a lock of this character and at the same time may be cheaply and economically constructed.

While we have shown and described some preferred embodiments of our invention, it will be understood that it is not to be limited to all of the details shown, but is capable of modification.

and variation within the spirit of the invention and within the scope of the appended claims.

What we claim is:

1. In a door lock, a lock case, a bolt slidably mounted therein, key-operated means at the outside of the door to operate the bolt, knob means at the inner side of the door to operate the bolt, additional means at the outside of the door to operate the knob, said knob means including a rotatable sleeve, a radially projecting arm on said sleeve, and means contacting said arm to limit rotation of the sleeve.

2. In a door lock, a lock case, a bolt slidably mounted therein, key-operated means at the outside of the door to operate the bolt including a spindle, a mounting element at the inside of the door, a rotatable member carried by said element and non-rotatably engaged with said spindle, a knob operatively connected to said member in alignment with said spindle, and a manually operable member at the outside of the door operatively connected to said rotatable member to actuate the same.

3. In a door lock, a lock case, a bolt slidably mounted therein, key-operated means at the outside of the door to operate the bolt including a spindle, a mounting element at the inside of the door, a rotatable member carried by said element and non-rotatably and slidably engaged with said spindle, a knob secured to said member in alignment with said spindle, and a manually operable member at the outside of the door operatively connected to said rotatable member to actuate the same.

4. In a door lock, a lock case, a bolt slidably mounted therein, a bolt-operating spindle passing transversely through the door, a key-operated lock at the outside of the door operatively connected with the spindle, a mounting plate at the inside of the door, a sleeve rotatably carried by said plate and slidably and non-rotatably engaged with said spindle, a knob secured to said sleeve, a pivoted latch mounted at the outside of the door, and means on said mounting plate connecting said sleeve with said pivoted latch whereby depression of the latch operates the sleeve.

5. In a door lock, a lock case, a bolt slidably mounted therein, a bolt-operating spindle passing transversely through the door, a key-operated lock at the outside of the door operatively connected with the spindle, a mounting plate at the inside of the door, a sleeve rotatably carried by said plate and slidably and non-rotatably engaged with said spindle, a knob secured to said sleeve, a pivoted latch mounted at the outside of the door, means on said mounting plate connecting said sleeve with said pivoted latch, said means comprising a lever pivotally mounted on the plate and actuated by the pivoted latch, and an arm on said sleeve engaged by said lever.

6. In a door lock, a lock case, a bolt slidably mounted therein, a bolt-operating spindle passing transversely through the door, a key-operated lock at the outside of the door operatively connected with the spindle, a mounting plate at the inside of the door, a sleeve rotatably carried by said plate and slidably and non-rotatably engaged with said spindle, a knob secured to said sleeve, a pivoted latch mounted at the outside of the door, means on said mounting plate connecting said sleeve with said pivoted latch, said means including a pair of cooperating levers mounted on said plate one above the other, the lower of said levers being engaged by the pivoted

latch, and an arm on the sleeve engaged by the other of said levers.

7. In a door lock, a lock case, a bolt slidably mounted therein, a bolt-operating spindle passing transversely through the door, a key-operated lock at the outside of the door operatively connected with the spindle, a mounting plate at the inside of the door, a sleeve rotatably carried by said plate and slidably and non-rotatably engaged with said spindle, a knob secured to said sleeve, a pivoted latch mounted at the outside of the door, means on said mounting plate connecting said sleeve with said pivoted latch, said means comprising a lever pivotally mounted on the plate and engaged with the pivoted latch, an arm on said sleeve actuated by said lever, and a stop on said plate engaging said arm to limit movement of said sleeve.

8. In a door lock, a lock case, a bolt slidably mounted therein, a bolt-operating spindle passing transversely through the door, a key-operated lock at the outside of the door operatively connected with the spindle, a mounting plate at the inside of the door, a sleeve rotatably carried by said plate and slidably and non-rotatably engaged with said spindle, a knob secured to said sleeve, a pivoted latch mounted at the outside of the door, means on said mounting plate connecting said sleeve with said pivoted latch, said means comprising a lever pivotally mounted on the plate and engaged with the pivoted latch, an arm on said sleeve actuated by said lever, and a stop on said plate engaging said arm to limit movement of said sleeve.

9. In a door lock, a lock case, a bolt slidably mounted therein, a bolt-operating spindle passing transversely through the door, a key-operated lock at the outside of the door operatively connected with the spindle, a mounting plate at the inside of the door, a sleeve rotatably carried by said plate and slidably and non-rotatably engaged with said spindle, a knob secured to said sleeve, a pivoted latch mounted at the outside of the door, an arm on said sleeve, a pivoted lever on said plate actuated by the pivoted latch, and a link connecting said lever with said arm.

10. In a door lock, a lock case, a bolt slidably mounted therein, a bolt-operating spindle passing transversely through the door, a key-operated lock at the outside of the door operatively connected with the spindle, a mounting plate at the inside of the door, a sleeve rotatably carried by said plate and slidably and non-rotatably engaged with said spindle, a knob secured to said sleeve, a pivoted latch mounted at the outside of the door, an arm on said sleeve, a pivoted lever on said plate actuated by the pivoted latch, a link connecting said lever with said arm, a stop member mounted on said plate, and means on the sleeve engaging said stop member to limit rotation of said sleeve.

11. In a door lock, a lock case, a bolt slidably mounted therein, a bolt-operating spindle projecting from the case, a mounting plate at the inside of the door, a sleeve rotatably carried by said plate and slidably and non-rotatably engaged with the spindle, a knob to operate said sleeve, a pivoted latch mounted at the outside of the door, a lever pivoted on the mounting plate to be actuated by the pivoted latch, and an arm on the sleeve actuated by said lever to rotate the sleeve.

12. In a door lock, a lock case, a bolt slidably mounted therein, a bolt-operating spindle projecting from the case, a mounting plate at the inside of the door, a sleeve rotatably carried by said plate and slidably and non-rotatably engaged

with the spindle, a knob to operate said sleeve, a pivoted latch mounted at the outside of the door, a lever pivoted on the mounting plate to be actuated by the pivoted latch, an arm on the sleeve actuated by said lever to rotate the sleeve, and a stop on said plate engaging the arm to limit movement of the sleeve.

13. In a door lock, a lock case, a bolt slidably mounted therein, a bolt-operating spindle projecting from the case, a mounting plate at the inside of the door, a sleeve rotatably carried by the plate and slidably and non-rotatably engaged with the spindle, a knob to operate said sleeve, a pivoted latch mounted at the outside of the door, an arm on said sleeve, a pivoted lever on said plate actuated by the pivoted latch, and a member interposed between said lever and arm to effect actuation of the latter by the former.

14. In a door lock, a lock case, a bolt slidably mounted therein, means to actuate said bolt including a spindle projecting into the case, a mounting element at the inside of the door, a rotatable member carried by said element and non-rotatably engaged with the spindle, a knob at the inside of the door operatively connected to said member in alignment with the spindle, and a manually operated member at the outside of the door also operatively connected to said rotatable member to actuate the same.

15. In a door lock, a lock case, a bolt slidably mounted therein, a bolt-operating spindle extending transversely into the case, a mounting plate at the inside of the door, a sleeve rotatably carried by said plate and slidably and non-rotatably engaged with the spindle, a knob operatively connected to said sleeve, a pivoted latch mounted at the outside of the door and extending through the door to a point adjacent said plate, and means on said mounting plate connecting said sleeve with said pivoted latch whereby depression of the latch operates the sleeve.

16. In a door lock, a lock case, a bolt slidably mounted therein, a bolt-operating spindle extending transversely into the case, a mounting plate at the inside of the door, a sleeve rotatably carried by said plate and slidably and non-rotatably engaged with the spindle, a knob operatively connected to said sleeve, a pivoted latch mounted at the outside of the door and extending through the door to a point adjacent said plate, and means on said mounting plate connecting said sleeve with said pivoted latch whereby depression of the latch operates the sleeve, said means comprising a lever pivotally mounted on the plate and actuated by the pivoted latch, and an arm on said sleeve actuated by the lever.

HENRY G. VOIGHT.
FRANK B. GERARD.
